UNITED STATES PATENT OFFICE.

JAMES H. CRAWFORD, OF CHICAGO, ILLINOIS.

REFRIGERATOR-CAR.

SPECIFICATION forming part of Letters Patent No. 593,012, dated November 2, 1897.

Application filed February 12, 1897. Serial No. 623,125. (No model.)

To all whom it may concern:

Be it known that I, JAMES H. CRAWFORD, a citizen of the United States, residing at Chicago, county of Cook, State of Illinois, have 5 invented a certain new and useful Improvement in Refrigerator-Cars; and I declare the following to be a full, clear, and exact description of the invention, such as will enable others skilled in the art to which it pertains to make and use the same, reference being had to the accompanying drawings, which form a part of this specification.

My invention relates to refrigerator-cars, and has for its object supplemental means 15 whereby additional cooling-surface may be afforded by the cold water obtained from the melting ice in the ice-bunkers or refrigerating-tanks proper.

Figure 1 is a longitudinal sectional view 20 through one end of the car, showing one of the ice-bunkers or refrigerator-tanks in elevation. Fig. 2 is a cross-sectional view through the car, that portion to the left of the central line being through the car-door, 25 while that portion to the right is taken near the end of the car with certain parts broken away. Fig. 3 is a side elevation of the ice-bunker or refrigerator-tank. Fig. 4 is a plan view of the same. Fig. 5 is a side view of 30 the auxiliary cooling-chamber. Fig. 6 is a view of the drip-cup. Fig. 7 is a cross-sectional view of the auxiliary cooling-chamber, showing the pipe connection with the ice-bunker and by arrows the direction of the 35 water in circulating through said auxiliary chamber toward the point of discharge.

In the drawings, A represents the car.

B is one of the ice-bunkers located, preferably, at each end of the car and supported 40 from below and on the sides by suitable timbers c, and provided with hatchway-doors D at the top.

E is an auxiliary cooling-chamber located adjacent to the ice-bunkers and preferably 45 formed of sheet metal and having dividing-walls e on the inside, as shown in Figs. 1 and 7. The walls e are separated to form an air-space e', so that the air in circulating may pass between the two cooling surfaces or 50 walls e in the chamber E.

G is a pipe leading out near the bottom of

the ice-bunker and connecting one side of the auxiliary cooling-chamber. From the top of this chamber, on the same side as the pipe just referred to, leads the pipe H, connecting at the bottom the channel on the opposite side of the auxiliary cooling-chamber. From the outside of the cooling-chamber E, near the top, is the pipe I, connected with the drain-pipe I', leading into the drip-cup J, located beneath the car. The upper portion I² of the pipe I' serves as an air-vent.

K is a pipe located near the bottom of the auxiliary cooling-chamber used in cleaning said chamber.

The drip-cup J is mounted beneath the bottom of the car and is preferably hinged, as shown, to afford easy access and is also provided with suitable means for securing the cup when in position. On the inside of 70 the drip-cup is an overflow-pipe j to carry off excess of water.

Leading out from the bottom of the ice chamber or tank B is the pipe B' under the control of a suitable valve. This is brought 75 in use when it is desired to clean or drain the ice-bunker.

The operation of my device is as follows: The ice bunker or tank having been properly charged, the water from the ice as it 80 melts will pass out through the pipe G and by natural pressure will rise in one side of the auxiliary cooling-chamber E until it reaches the top. It will then flow down through the inclined pipe H until it reaches 85 the opposite side of the cooling-chamber, when it will again begin to rise until it reaches the top, when it will pass out through the pipe I, which, by means of the pipe I', will conduct the water to the drip-cup J. Here 90 a water seal or trap is formed by the pipe j, in order that it may effectually prevent the warm air from the outside securing an entrance into the car.

What I claim is—

1. In a refrigerator-car, the combination of an ice-bunker, an auxiliary cooling-chamber having dividing-walls therein forming channels for the passage of water, and an air-space between the same, pipes connecting the ice-bunker with the cooling-chamber, means to afford communication from one side of the

cooling-chamber to the other, and pipes for conducting the water to a point of discharge, substantially as described.

2. In a refrigerator-car, the combination
5 of an ice-bunker, an auxiliary cooling-cham-
ber having dividing-walls therein forming
channels for water, said channels separated
so as to form an air-space between the same,
pipes connecting the ice-bunker with the
10 cooling-chamber, means to afford communica-
tion from one side of said cooling-chamber
to the other, pipes for carrying off the water
from the cooling-chamber, and a trap located
on the line of said pipes near the point of
15 discharge substantially as described.
3. In a refrigerator-car, the combination

of an ice-bunker, an auxiliary cooling-cham-
ber having dividing-walls therein forming
channels for the passage of water, and an air-
space between the same, pipes connecting the
ice-bunker with the cooling-chamber and
20 vent-pipe I² leading to said auxiliary cham-
ber, and a pipe K located near the bottom of
the cooling-chamber whereby the same may
be cleaned, substantially as described. 25

In testimony whereof I sign this specification
in the presence of two witnesses.

JAMES H. CRAWFORD.
